UNITED STATES PATENT OFFICE.

WILLIAM J. BRETT, OF BROOKLYN, NEW YORK.

HAIR-WAVER.

1,139,398.

Specification of Letters Patent.

Patented May 11, 1915.

Application filed July 19, 1913. Serial No. 779,924.

To all whom it may concern:

Be it known that I, WILLIAM J. BRETT, a citizen of the United States, and resident of Brooklyn, in the county of Kings and State 5 of New York, have invented certain new and useful Improvements in Hair-Wavers, of which the following is a specification.

This invention relates to hair-wavers, its object being to provide a device of simple 10 and efficient construction and operation whereby a variable wave effect can be readily imparted to the hair.

To this end the invention comprises a flexible non-elastic twisted body portion 15 around which a dampened strand of hair may be spirally wound or rolled, and the ends of such body then be bent over to maintain the hair in position.

The invention also comprises features of 20 construction whereby advantages are gained, as will be hereinafter described and claimed.

In the drawings—Figures 1 and 2 are elevations of a hair-waver embodying my invention, showing different twists or adjustments of the body. Fig. 3 is a view, enlarged, of the free end of one of the members of the device, the same being represented partly in vertical section to show more clearly the protective pad extension 30 of the covering for the central metal core.

My improved hair-waver, in the form herein selected for illustration, comprises a flexible non-elastic body portion composed preferably of a central metallic core, *a*, of 35 soft copper wire, a covering of rubber, *b*, on the core, and a covering of braided thread, *c*, on the rubber, the external covering being sufficiently extended at the free ends of the wire to serve as a pad or guard 40 for the latter, as indicated at *d*.

The body is doubled upon itself and the two members are twisted together to produce a spiral of any desired length of coil or pitch extending from a loop at the end 45 of the device, such as illustrated in Figs. 1 and 2, the non-elastic character of the pliable metal core permitting the easy twisting of the members and also maintaining the parts effectually in the spiral form 50 which they may be caused to assume.

The spirally twisted form of the two parts of the waver provides longitudinally ex-

tending ridges and valleys for the greater part of the length of the device. These ridges with the intervening valleys are the 55 effective feature in giving a crimp, wave or curl to the hair.

To use the device a tress or lock of hair is dampened slightly and twisted to form a slim strand. This strand is then rolled 60 tightly around the device beginning at or adjacent the scalp and following the spiral form. The ends of the device are then bent over upon the spiral body to maintain the hair in position thereon. If desired a hair pin 65 may be used to fasten the loose end of the hair. The device being maintained upon the head for a sufficient period it is removed from the strand of hair, which latter when combed out presents a wave-like appearance with undulations of greater or less 70 length as defined by the twist of the coiled body.

It is to be noted that the rubber covering not only imparts the requisite softness and 75 bulk to the device, without impairing the flexibility of the latter, but it also protects the metal core from the action of the damp hair. The braided covering, which may be any suitable color, conceals and protects the 80 rubber and adds to the attractiveness of the device.

An important feature of my invention lies in the adjustability, so to say, of the spiral form of the body, as the user, by merely 85 twisting the two members of such body more or less, can vary the size or length of the spiral as desired.

I claim as my invention—

1. A hair-waver comprising a body composed of a flexible non-elastic metallic core and a soft flexible covering thereon, said body being doubled upon itself and the two lengths thus formed being twisted together to produce a variable spiral.

2. A hair-waver comprising a doubled and twisted body portion composed of a flexible non-elastic metallic core, a covering of rubber on the core, and a covering of braided thread on the rubber.

3. A hair-waver comprising a doubled and twisted body portion composed of a flexible non-elastic metallic core, a covering of rubber on the core, and a covering of

braided thread on the rubber, said braided thread being extended beyond the extremities of the core to provide a pad or guard for the latter.

4. The herein described hairwaver comprising in combination, a pliable metal core and a pliable non-metallic covering, with a loop at one end and with two parts twisted together from the loop to the opposite end,

providing spiral ridges and intervening valleys, substantially as described.

Signed at New York in the county and State of New York this 18th day of July A. D. 1913.

WILLIAM J. BRETT.
